UNITED STATES PATENT OFFICE.

SAMUEL Q. McCLURE, OF AKRON, OHIO.

DESIGN FOR A DICTAPHONE-RECORD CABINET.

55,869.

Specification for Design.

Patented July 20, 1920.

Application filed August 20, 1919. Serial No. 318,821. Term of patent 7 years.

To all whom it may concern:

Be it known that I, SAMUEL Q. McCLURE, a citizen of the United States, residing at Akron, in the county of Summit and State of Ohio, have invented a new and original Design for a Dictaphone-Record Cabinet, of which the following is a specification, reference being had to the accompanying drawing, forming a part thereof.

In said drawing, Figure 1 is a perspective view, and

Fig. 2 is a fragmentary front elevation of my design.

I claim:

The design for a dictaphone record cabinet substantially as herein shown.

SAMUEL Q. McCLURE.
